UNITED STATES PATENT OFFICE.

EDGAR VAN BAVEGEM, OF OOSTERZEELE, BELGIUM.

METHOD OF CONSTRUCTING REINFORCED CONCRETE STRUCTURES.

1,398,209.

Specification of Letters Patent.

Patented Nov. 22, 1921.

Application filed May 21, 1919. Serial No. 298,606.

To all whom it may concern:

Be it known that I, EDGAR VAN BAVEGEM, a subject of the King of Belgium, and a resident of the village of Oosterzeele, Flanders, Belgium, have invented a new and Improved Method of Constructing Reinforced Concrete Structures, of which the following is a full, clear, and exact description.

This invention relates to reinforced concrete structures. According to the invention, hollow walls of reinforced concrete are molded complete, in a horizontal position, with window casement and door frames, and cornices where required. The mold receives the concrete to form the outside wall surface, into which metallic reinforcement with inwardly projecting strengthening ribs is laid and covered with concrete, after which the cavities are filled with sand, and an inner wall is formed by molding over the projecting reinforcing ribs. The sand can then be removed through openings. Each wall when erected afterward, consists of inside and outside wall faces with vertical reinforced concrete connections for strength, both wall faces being completely molded and finished. Monoblock wall units made in this way are easily joined together and to other parts of the structure, either removably by means of bolts, or in a permanent manner with reinforcing bars embedded at the joints, to make a monoblock structure.

Each wall section made as above described is complete from basement to cornice. It can be transported where necessary, and is very well adapted for use in building comparatively small structures such as cottages or bungalows.

Drawings.

40

Figure 1 is a perspective view of the mold;

Figs. 2 and 3 are two perspective views showing the method of molding the reinforced concrete outer wall with its strengthening ribs;

Fig. 4 illustrates in perspective, in outline, a suitable form of metallic reinforcement with strengthening ribs, window and door frames, base and cornice, ready for use in the mold;

Fig. 5 is a perspective view of the inner wall surface;

Figs. 6, 7, 8 and 9 show sections of joints between walls, illustrating different methods

of making the joints between the wall sections;

Fig. 10 shows in section the top of a wall with a projecting terrace, and it also illustrates part of a reinforced concrete ceiling; 60

Fig. 11 shows in vertical section a complete wall, and a part of a ceiling, and flat roof;

Fig. 12 shows in horizontal section parts of the walls, both external and internal, of 65 a house.

Description.

The horizontal mold as in Fig. 1, is prepared as follows: It has a thick bed *a* of 70 clay, for example, or any other suitable molding material, and two retaining walls *b* and *c*. On this are arranged four adjustable walls or boards *d*, *e*, *f*, *g*, which are adjusted according to the dimensions of the 75 wall section to be made.

In molding an outside wall, I press into the layer *a* the properly shaped molding forms, using a flat-bottomed press. The press and the forms are removed, and the 80 shaped clay surface is coated with oil or the like to prevent the concrete from adhering to the clay; then, with the retaining boards *d*, *e*, *f*, *g*, properly adjusted, I run in the first layer of concrete. When the 85 concrete layer has been introduced, I insert as in Figs. 2 and 3, the metallic reinforcing structure *h*, formed of suitable material such as metal net, and shaped as seen in Fig. 4 for instance. This structure may be provided with a base *i*, a cornice *j*, window and door frames *k*, *l*, and several vertical reinforcing ribs *m*. It also has rings or staples *n* projecting beyond the ribs and serving for lifting and transporting the wall when 95 molded. When this reinforcing structure is laid on the first layer of concrete, another run of concrete is applied over it to embed it, the concrete being shaped up over the projecting ribs with a suitable tool to incase 100 them up to about an inch from the top.

When this part of the molding is finished, the spaces between the reinforcing ribs and the like are filled in with sand as high as the concrete on the reinforcing ribs, *i. e.*, 105 about an inch from the top; then a flat metallic reinforcing net-work with window and door apertures is attached over the surface of the molded portion, and is embedded in a layer of concrete or cement, stucco, or 110

the like, which is run over it to form the inner wall surface *p*. This surface is finished in any way required, with or without shaped moldings. Any door or window frames are inserted with the outside reinforcing network and thus embedded in the outer wall layer, projecting through to the inner layer. When the wall is set, the sand is taken out through the open ends of the 5 cavities at the top end of the wall, and through openings *o* left in the inner wall surface where necessary as in Fig. 5. The complete wall can then be lifted by tackle attached to the rings *n* exposed through 10 holes *y* in the inner wall surface, and transported to the place where the building is to be erected.

Wall sections can be joined together in the structure to form either removable or 20 permanent connections as required. Figs. 6 and 7 show the method of making a permanent joint. Projecting retaining pieces *q* are formed in the walls by extensions of the metallic reinforcement, and when the wall 25 sections are brought together, the gaps *t* at the joints are filled with concrete in which are embedded angle bars of L or T shape as required, at suitable distances apart.

Removable joints are made as in Figs. 8 30 and 9; holes to receive bolts are formed at suitable intervals in the wall ends, and bolts and ties *r*, *s* are used to hold the sections together. The space in the gaps *t* is filled in with concrete, as seen in Fig. 12.

35 The ceilings *v* may be made up of slabs molded in a similar manner to the walls, and of a length sufficient to extend over the whole length of the space to be covered, while their width may be any convenient 40 unit. Adjacent slabs fit together with joggled joints as at *u*, Fig. 10. If a projecting coping or terrace is to be provided, the tops of the walls are surmounted with blocks formed with projecting portions *w*. 45 If a flat roof is needed, this is made up in sections *x* fitted together in suitable widths as in Fig. 11.

The complete building forms thus a unitary structure made up of ready molded 50 monoblock sections, and the labor of erection is made as simple as possible. In the example of construction illustrated, the reinforcing network for the wall is flat, with

the window and door apertures, and with its ends bent up to form the cores of the 55 bottom and top beams *i* and *j*, strengthened by curved connecting pieces *z*. The ribs *m* are formed by attached strips of the network or the like as also are the borders of the window and door apertures *k*, *l*. 60

Claims.

1. The herein described method of constructing concrete walls consisting in shaping a recumbent mold having a bed of clay, 65 coating the clay with oil, pouring a thin layer of concrete into the mold, then placing on the first layer of concrete a ribbed reinforcing structure having door and window frames conforming to the shape of the mold 70 and having upwardly projecting staples attached thereto, then pouring in a second thin layer of concrete to embed the edges of the reinforcing structure, then placing a layer of sand upon the concrete, leaving only 75 the edges of the reinforcing structure and the staples exposed, then pouring in another layer of concrete and leaving openings in this last mentioned layer to expose the staples, then raising the wall and removing 80 the sand.

2. The herein described method of constructing concrete walls consisting in shaping a recumbent mold having a bed of clay, 85 coating the clay with oil, pouring a thin layer of concrete into the mold, then placing on the first layer of concrete a ribbed reinforcing structure having door and window frames conforming to the shape of the mold and having upwardly projecting 90 staples attached thereto, then pouring in a second thin layer of concrete to embed the edges of the reinforcing structure, then placing a layer of sand upon the concrete, leaving only the edges of the reinforcing structure and the staples exposed, then pouring in another layer of concrete and leaving openings in this last mentioned layer to expose the staples, then attaching 95 suitable hoisting apparatus to the staples and raising the wall and then removing 100 the sand.
